LOUDSPEAKER

Barney Rigney, Jr., Los Angeles, Calif., assignor to
Sound West, Inc., Van Nuys, Calif.

Filed Oct. 27, 1972, Ser. No. 301,586

Term of patent 14 years

Int. Cl. D14—01
U.S. Cl. D26—14 G

FIG. 3

FIG. 4

FIG. 1 is a front view of my loudspeaker showing my new design;

FIG. 2 is a side view of FIG. 1;

FIG. 3 is a front view of a modified form of my loudspeaker;

FIG. 4 is a side view of FIG. 3;

FIG. 5 is a front view of a further modified form of my loudspeaker; and

FIG. 6 is a side view of FIG. 5.

The undisclosed rear portions of the claimed loudspeaker embodiments are plane and unornamented.

I claim:

The ornamental design for a loudspeaker, as shown and described.
